J. H. Stickney, of East Cambridge, Mass.
Letters Patent No. 2031. Dated Feb. 14-1865.
Design for a Burial Case.

The schedule referred to in these Letters Patent and making part of the same.

Small whom it may concern:

Be it known that J. H. Stickney, of East Cambridge, in the County of Middlesex and State of Massachusetts, have invented or produced a new and ornamental design for a Burial Casket, and I do hereby declare that the following, taken in connection with the drawings which accompany and form part of this specification, is a description of the design sufficient to enable those skilled in the art to practice it.

This design is intended for the ornamentation of the sides and ends and tops of Burial Caskets. It consists of panels which are surrounded by mouldings. Also of a moulding, under the lid, all as seen in the drawings which represent respectively, side, end and top views of a casket embodying my design.

In witness whereof I have hereunto set my hand, this sixteenth day of January A.D. 1865.

Witness:

Francis Gould
W. B. Gleason.
